UNITED STATES PATENT OFFICE

125,299

DESIGN FOR A BASEBALL CLOCK

William Harrison Wayman, Detroit, Mich.

Application June 7, 1940, Serial No. 92,868

Term of patent 3½ years

To all whom it may concern:

Be it known that I, William Harrison Wayman, a citizen of the United States, residing at Detroit, in the county of Wayne and State of Michigan, have invented a new, original, and ornamental Design for a Baseball Clock, of which the following is a specification, reference being had to the accompanying drawing, forming part thereof.

Figure 1 is a front elevational view of the baseball clock, showing my new design.

Figure 2 is a side elevational view of the same. The appearance of the opposite side of the design is substantially the same as that of the side shown.

I claim:

The ornamental design for a baseball clock, as shown and described.

WILLIAM HARRISON WAYMAN,
